UNITED STATES PATENT OFFICE.

THOMAS WHEATLEY, OF SYRACUSE, NEW YORK.

AIR-VALVE.

SPECIFICATION forming part of Letters Patent No. 772,765, dated October 18, 1904.

Application filed April 1, 1902. Serial No. 100,982. (No model.)

To all whom it may concern:

Be it known that I, THOMAS WHEATLEY, of Syracuse, in the county of Onondaga, in the State of New York, have invented new and 5 useful Improvements in Air-Valves, of which the following, taken in connection with the accompanying drawings, is a full, clear, and exact description.

This invention relates to improvements in 10 air-valves for radiators and similar heating apparatus.

The primary object of this invention is to permit the free displacement of the air from the radiator by the inflowing heating fluid.

15 Another more specific object is to obviate the liability of any leakage from the shell without the use of any stuffing-box or other packing for the adjusting parts.

Another object is to provide means whereby 20 the air-vent is closed automatically by the influx of the cold water of condensation in the radiator by the inflowing heating fluid.

A further object is to provide a movable 25 well and adjusting means for varying the position of the well relative to the air-vent, and a still further object is to control the valve automatically by means of an expansible fluid sensitive to terminal changes.

To this end the invention consists in the 30 combination, construction, and arrangement of the parts of an air-valve, as hereinafter fully described, and pointed out in the claims.

Referring to the drawings, Figure 1 is a 35 vertical sectional view of the device embodying the various features of my invention. Figs. 2 and 3 are sectional views taken, respectively, on lines 2 2 and 3 3, Fig. 1.

Similar reference characters indicate corresponding parts in all the views.

40 In Figs. 1, 2, and 3 of the drawings I have shown my invention as consisting of a shell 1 and a valve 2, a fluid-containing space 3, a float 4, and a well 5, which is movable toward and from the vent.

45 The shell 1 may be of any desired form, size, or construction, and preferably consists of a base 6, an upright cylinder 7, and a nipple 8, said parts being permanently secured to each other in any desired manner not nec-

essary to further illustrate or describe, the 50 essential requirements being that the joints between the parts are absolutely tight to prevent the leakage of steam, water, or air.

The base 6 is provided with an inlet-opening 9, extending laterally from and communicating with its interior chamber 10, and is also provided with a threaded aperture 11 in its bottom wall for receiving an adjusting-screw 12, the function of which will be presently described.

60 The upright cylinder 7 is hollow, its lower end being open and communicating with the chamber 10, and its upper end is closed and provided with a nipple 8, said nipple being formed with an air-outlet passage 13, leading 65 from the interior of the shell 7 to the atmosphere.

The inner end of the nipple 8, which, if desired, may be formed integral with the cylinder 7, is provided with a valve-seat 14, 70 adapted to receive the valve 2. This valve 2 may be of any desired form or construction and supported in any suitable manner to be operated either by the expansion of the fluid in the space 3 or by the float 4, which operation by the expansible fluid or float may be either simultaneous or by the float individually.

75 As seen in Fig. 1, the expansible body in the space 3 is hermetically sealed in a suitable inclosing case 15, having lower and upper flexible walls or diaphragms 16 and 17, and suitably secured to the walls of the shell 1 in such manner that the intermediate portions of the diaphragms are free to move or 80 to be moved toward and away from each other or independently of each other. The preferable mode of securing this inclosing case for the expansible fluid is to attach the perimeter of the base of the case to the adjacent walls 90 of the base 6 by soldering or sweating or otherwise permanently attaching the adjacent parts, so as to form a tight joint surrounding the inner end of the aperture 11, which prevents the escape of any steam or other heating fluid through said aperture even though the adjusting-screw 12 may be removed. This 95 is a particularly important feature of my in-

vention, for the reason that it obviates the necessity of any packing around the adjusting-screw.

In the construction and operation of the case 15 just described said case is first filled with the expansible fluid, and then the walls are sealed, so as to prevent any evaporation or loss of fluid therefrom. Any desired material may be employed in the case 15 which 5 is susceptible to expansion and contraction under varying degrees of temperature, so that when the temperature is normal the diaphragm 17 is depressed and as the degree of temperature increases the fluid in the casing 15 expands and elevates the diaphragm 17. This elevation and depression of the diaphragm is utilized to operate the valve 2, and any desired means may be employed for transmitting motion from said diaphragm to 10 the valve, this means in Fig. 1 consisting of a rod or stem 19 having one end connected to the valve and its other end loosely seated in a socket 20, formed in a head 21, projecting upwardly from the center of the diaphragm 17, said head being usually permanently secured to the diaphragm. It is thus 15 apparent that when the fluid in the casing 15 is heated by the heating fluid passing into the shell through the passage 9 said fluid is expanded and elevates the diaphragm 17, which in turn operates to close the valve 2 through the medium of the head 21 and stem or rod 19, and when the temperature of the fluid lowers the diaphragm retracts automatically, 20 thereby permitting the valve 2 and stem 19 to return to their normal inoperative positions for opening the passage 13.

It is sometimes necessary to adjust the valve relative to its seat, particularly when the means 25 for automatically moving the valve is incapable of operating the valve sufficiently to close the passage at the proper time, and for this purpose I provide an adjusting-screw 12, which, as seen in Fig. 1, is movable in the threaded aperture 11 and is adapted to engage the lower diaphragm 16 at substantially its central point for the purpose of moving said diaphragm, from which motion is transmitted to the upper diaphragm 17 through 30 the medium of the fluid in the casing 15.

The well 5 is mounted upon the diaphragm 17 of the casing 15, and is therefore movable with said diaphragm toward and from the air-vent 13 and is operated by the expansion and 35 contraction of the liquid in the case 15 or by the adjusting-screw 12 through the medium of the diaphragms 16 and 17 and the liquid in said case. The bottom of the well is imperforate; but its upper end is open and receives 40 the lower end of the float 4, which is shown as supported on the upper end of the stem 19, while its lower end is open and extends into and beneath the top of the well, so that any water of condensation rising in the shell and 45 overflowing in the well traps the air in the

float and causes it to rise and close the valve, while at the same time the inflowing heating agent operates to expand the fluid in the casing 15 and also to expand the trapped air in the float and adds additional pressure to close 70 the valve to prevent the escape of steam or water through the outlet.

The only means of escape of the water from the well is by overflow at the top, and therefore more or less water of condensation remains in the well to trap the air in the float; but this liquid is also expanded by the heating agent and further operates to keep the valve closed as long as the heat is present in the shell. This expansion of the water of condensation in the well causes an overflow of the excess into the shell while the valve remains closed; but in the absence of heat this water recedes in the well, and the other expansible elements also relax and permit the valve to 80 open, whereupon the valve-operating elements are again in position for a repetition of the operation just described.

Having thus described my invention, what I claim, and desire to secure by Letters Pat- 90 ent, is—

1. In an air-valve for radiators, a shell having an inlet and an outlet, a well in the shell, a float in the well, a valve actuated by the float to close the outlet, and means to move the 95 well toward and from the outlet.

2. In an air-valve for radiators, a shell having an inlet and an outlet, a valve for the outlet, and a movable well operatively connected to actuate the valve.

3. In an air-valve for radiators, a shell having an inlet and a valved outlet, a float operatively connected to actuate the valve, a well adjustable relatively to the float, and means to adjust the well.

4. In an air-valve for radiators, a shell having an inlet and a valved outlet, a well in the shell, a float in the well operatively connected to actuate the valve, and means in the well to guide the float.

5. In an air-valve for radiators, a shell having an inlet and a valved outlet, a well in the shell movable toward and from the outlet, means to move the well, and a float in the well operatively connected to actuate the valve.

6. In an air-valve for radiators, a shell having an inlet and a valved outlet, a well in the shell movable toward and from the outlet, means to move the well, a float in the well operatively connected to actuate the valve, and means in the well to guide the float.

7. In an air-valve for radiators, the combination with a shell having an inlet and a valved outlet, a well in the shell movable toward and from the outlet and having an imperforate bottom, a float in the well having an open bottom and operatively connected to actuate the valve, and means in the well to guide the float.

8. In an air-valve for radiators, the combination of a base or cup having an interior 130

chamber and a neck with an inlet opening into the interior chamber, an outer shell fixedly entered into the base and having its top or upper end provided with a vent-passage, an 5 inner well open at the top and having an imperforate bottom above the inlet, said well being adjustable vertically and of less diameter than the outer shell leaving a channel or passage between the sides of the well and shell, 10 a float loosely entered into the open end of the well and of less diameter than the diameter of the well, leaving a space between the sides of the float and well, and a valve carried by the float for closing and opening the vent- 15 passage with the rise and fall of the float and well, and means to adjust the well vertically.

9. In an air-valve for radiators, a base having an inlet, a shell fixed to the base and provided with an air-outlet, a well in the shell having an open top and an imperforate bottom 20 above the inlet and a float inserted in the open end of the well and a valve actuated by the float to open and close the outlet, and means to move the well toward and from the outlet-passage. 25

In witness whereof I have hereunto set my hand this 27th day of March, 1902.

THOMAS WHEATLEY.
